UNITED STATES PATENT OFFICE.

MAHLON E. LAYNE, OF HOUSTON, TEXAS.

WELL MECHANISM.

No. 910,696.

Specification of Letters Patent.

Patented Jan. 26, 1909.

Application filed December 10, 1907. Serial No. 405,957.

To all whom it may concern:

Be it known that I, MAHLON E. LAYNE, a citizen of the United States, residing at Houston, in the county of Harris and State 5 of Texas, have invented certain new and useful Improvements in Well Mechanisms, of which the following is a specification.

The invention relates to well apparatus of the type shown in my co-pending application 10 Serial No. 404,969, filed December 3rd, 1907 wherein the pit casing is secured to the top of one of the well casing sections. The invention has for its objects; the provision of an improved and simplified type of coupling in 15 which an absolutely tight joint is secured between the coupling sleeve and the coupling member employed, and the provision of a coupling which shall give a rigid attachment of the parts and one of maximum strength. One 20 embodiment of the invention is illustrated in the accompanying drawings, wherein:—

The figure is a longitudinal section through the coupling members.

The invention constitutes a modification 25 of the invention shown in my co-pending application, Serial No. 404,969, filed December 3rd, 1907, and as the departure relates only to the coupling, the rest of the mechanism is not illustrated. Referring to 30 the drawing, 1 is the pit casing, the lower end only of which is shown, 2 is the coupling member which is a casting riveted to the interior of the pit casing, and provided with the downwardly projecting flange 3 carrying 35 the coarse spiral thread 4, 5 and 6 are sections of the well casing which extend through the pit casing, 7 is the coupling sleeve threaded to the sections 5 and 6 and provided on its exterior with the coarse thread 40 8 coöperating with the thread 4 on the coupling member 2, and 9 are the cutter members which are secured to the casting and which cuts away the material when the

pit casing is rotated. The threads 4 and 8 are arranged on an incline so that after the 45 member 2 has rotated a sufficient distance it will be brought to a positive stop and the parts thus locked rigidly together, and a tight joint secured. The taper might of course be omitted, although the construction illustrated and described is preferred. It will be seen that various modifications in the form of thread used, and the manner of its application might be made without avoiding the broad invention involved. It 50 will be understood that in this construction, as in that of my co-pending application, the upper well section 5 is removed after the coupling members 2 and 7 are brought to the position shown in the figure. 55

Having thus described my invention and illustrated its use, what I claim as new and desire to secure by Letters Patent is the following:—

1. In combination, a pit casing, a coupling member secured thereto and provided with a coarse spiral thread, a pair of casing sections, and a coupling sleeve therefor provided on its exterior with a spiral thread adapted to coöperate with the first men- 65 tioned thread.

2. In combination, a pit casing, a coupling member secured thereto and provided with a coarse spiral thread, a pair of casing sections, and a coupling sleeve therefor provided on its exterior with a spiral thread 70 adapted to coöperate with the first mentioned thread, the coöperating threaded members being tapered.

In testimony whereof I have hereunto 80 signed my name in the presence of the two subscribed witnesses.

MAHLON E. LAYNE.
